US0D1080812S

(12) **United States Design Patent** (10) **Patent No.:** **US D1,080,812 S**
(45) **Date of Patent:** **** Jun. 24, 2025**

(54) **GAS MIXER**

- (71) Applicant: **Applied Materials, Inc.**, Santa Clara, CA (US)
- (72) Inventors: **Youngki Chang**, Santa Clara, CA (US); **Dhritiman Subha Kashyap**, Bangalore (IN); **Rakesh Ramadas**, San Jose, CA (US); **Ashutosh Agarwal**, San Jose, CA (US); **Shashidhara Patel H B**, Karnataka (IN); **Muhannad Mustafa**, Milpitas, CA (US); **Sanjeev Baluja**, Campbell, CA (US)
- (73) Assignee: **Applied Materials, Inc.**, Santa Clara, CA (US)
- (**) Term: **15 Years**
- (21) Appl. No.: **29/857,731**
- (22) Filed: **Oct. 25, 2022**

(57) **CLAIM**

The ornamental design for a gas mixer, substantially as shown and described.

DESCRIPTION

FIG. 1 is a top-front-right isometric view of a gas mixer according to a first embodiment;

FIG. 2 is a bottom-rear-left isometric view of the gas mixer of FIG. 1;

FIG. 3 is a front view of the gas mixer of FIG. 1;

FIG. 4 is a rear view of the gas mixer of FIG. 1;

FIG. 5 is a left side view of the gas mixer of FIG. 1;

FIG. 6 is a right side view of the gas mixer of FIG. 1;

FIG. 7 is a top view of the gas mixer of FIG. 1; and,

FIG. 8 is a bottom view of the gas mixer of FIG. 1.
